UNITED STATES PATENT OFFICE.

BERTON J. PARSON, OF JOLIETTE, NORTH DAKOTA.

SACK-HOLDER.

992,445.

Specification of Letters Patent. Patented May 16, 1911.

Application filed June 4, 1910. Serial No. 565,021.

To all whom it may concern:

Be it known that I, BERTON J. PARSON, a citizen of the United States, residing at Joliette, in the county of Pembina and State 5 of North Dakota, have invented a new and useful Sack-Holder, of which the following is a specification.

My invention relates to sack-holders; and the object is to provide a cheap, simple yet 10 efficient device for holding a sack open while it is being filled with grain, potatoes or any other substance for which sacks are used.

The accompanying drawing is a perspective front view of my sack-holder and a 15 piece of board for holding it.

Referring to the drawing by reference numerals, 1 designates a piece of board adapted to be nailed at one end to any kind of upright, such as a post or studding or the 20 door frame of a granary, barn, cellar or other place where sacks are to be filled. The sack-holder proper is supported on said board in the manner shown, with its main loop 2 hanging down at the rear of the 25 board and all the rest of it positioned forward of the board.

The holder is formed of a single piece of wire or round bar iron of about five-sixteenths of an inch diameter; said bar being 30 bent at the middle to form the U-shaped loop 2; each half bar is then bent forward to form loops 3, then downward to form loops 4, then upward to form loops or horns 5, then downward to point 6 and thence outward 35 laterally to form arms 7, the outer ends of which are formed with a rearward eye 8, and the balance of the bar is directed forwardly to form almost parallel arms 9.

In the use of the holder the edges of the 40 open end of the sack is placed rearwardly over the horns 5 and slipped down in rear thereof; the rest of the edge is similarly thrown upon and outward over the arms 7, loops 8 and arms 9, so that the sack is suspended 45 between the four arms, and its free edge extends across between the free ends of the arms 9. The bottom of the sack may

preferably rest on the floor. When the sack thus held open is filled it is removed from the holder and replaced by an empty sack. 50

To enable the sack-holder to be suspended from a nail or peg when so desired, I provide the upper end of the holder with a metallic strap or plate 11, having a hole 12 to go on a peg secured in any wall or other 55 object. In the simplest form of the holder I omit the strap or plate 11 and simply invert the holder and hang the loop 2 on the peg. When this is done the rear edge of the suspended sack enters into the loops 5 60 instead of into the loops 4; and if the sack is very large the edge may be placed in the loops 3, which loops in that case have no board in them. In all cases it will be understood that the arms and their loops shown 65 are springy so as to spread into holding engagement with sacks of uneven sizes.

It will thus be seen that I provide a sack-holder from a single piece of iron which while either hot or cold may easily and 70 quickly be bent by suitable tools into the shape shown.

What I claim is:—

A sack-holder formed of a single metal bar, said bar being bent at the middle to 75 form a U-shaped loop, said loop being bent to form a broad hook adapted to take over an object for supporting the holder; the remaining portions of the bar extending from said loop on each side thereof being each 80 curved forward, thence upward, thence forward and downward to form the loops or horns for holding the sack, thence outward in opposite directions, then formed each 85 with an eye loop, then directed forward from the latter loops to form two parallel arms adapted to engage within the opening of the sack and aid in supporting it.

In testimony whereof I affix my signature, in presence of two witnesses.

BERTON J. PARSON.
